DESTRUCTIBLE LINK DEVICE

Lucien Guy Dejean, Paris, France, assignor to Societe Nationale de Constructions Aeronautiques du Sud-Ouest, Paris, France

Application May 10, 1955, Serial No. 507,371

Claims priority, application France May 18, 1954

1 Claim. (Cl. 244—138)

This invention relates to a device comprising a link for temporarily attaching two bodies together, the said device comprising means to partly destroy said link, so as to cause automatic disconnection of said bodies.

One object of the invention is to provide a device of this type which, while being extremely simple and cheap, is nevertheless capable of ensuring a safe and reliable attachment of the two bodies, as long as the said link destroying means are not operated, as well as a safe disconnection upon operation of the said means.

A more specific object of the invention is to provide a device of the type described, wherein the said partly destructive link is constituted by a tubular braid made of textile or metal fabric and wherein the said link destroying means are constituted by a blasting cartridge which has been introduced into said tubular braid through an enlarged mesh of the fabric without breaking of the threads or wires, means being provided for firing the said cartridge from outside the braid.

There is thus provided an extremely simple destructible link device and the mechanical resistance of the braid is not impaired.

Moreover, when the said braid is subjected to a tensile stress, it compresses the cartridge thus increasing the blasting power of the same while the threads or wires to be broken are thus tightly pressed against the cartridge, which makes their destruction safer.

Still another object of the invention is to ensure remote firing of the above mentioned cartridge through a slow-match of conventional type, which permits delaying the said firing and hence the desired disconnection by any desired time.

The invention finds a particularly interesting application in parachutes provided with an extracting canopy for delaying the opening of the main canopy by temporarily anchoring the said extracting canopy on the load.

Other objects and advantages of the invention will be apparent from the following detailed description, together with the accompanying drawing, submitted for purposes of illustration only and not intended to define the scope of the invention, reference being had for that purpose to the subjoined claim.

On these drawings:

Fig. 1 is an elevational view of a destructible connecting means according to the invention;

Fig. 2 is an interrupted longitudinal section of the pyrotechnical portion of the device shown in Fig. 1; and

Fig. 3 shows the application of the invention to the delayed opening of a parachute.

The tubular braid 1 shown in Fig. 1 is formed either of metal wires or threads made of any suitable natural or artificial textile material.

It is well known that when such a braid is not taut, it is possible to insert a spike into a mesh of the fabric in order to move the threads or wires apart without breaking them so as to provide access to the inner conduit of the braid.

An explosive cartridge 2 (Fig. 2) containing a load 3

of powder or explosive substance may thus be introduced into said braid. This powder may be, for instance, blasting powder.

The casing 2 of the cartridge may be of any material and, preferably, paraffined cardboard or plastic material, for instance a vinyl compound. In the case where the braid has a small inner diameter and is made of textile threads, said cartridge may be a mere tube of thermoplastic material with an inner diameter equal to that of the slow match 4 and having one end thereof threaded over said slow-match while the other end of said tube is obturated by being crushed or twisted subsequent to a suitable heating operation.

The length of the slow-match 4 is proportional to the desired delay of operation (as a rule 1 centimeter per second). The opposite end of the slow-match 4 is furnished with an igniting device 5 which, in a known manner, may be a tube adapted to cover the match and partially filled with a fulminating compound 6 into which is embedded a barbed wire 7 terminating into a pull ring 8.

Upon the barbed wire being torn up, the fulminating compound is fired and lights up the slow match which causes the cartridge to explode after the aforesaid desired delay.

When a metal braid is used, the cartridge 2 may contain a high explosive material and may be provided with a detonator.

When the braid 1 is taut, the threads or wires which it is made of are pressed close to each other and snugly fit against the cartridge thus compressing it.

The explosion of the cartridge, thus, is able more easily to destroy all the wires at once.

In Fig. 3, the braid 1 forms, by splicing, stitching or knotting, a closed loop engaged, on one hand, into a ring 9 rigid with a load to be parachuted and, on the other hand, into a ring 10 arranged at the foot of the shroud lines of an extracting parachute.

The extracting parachute spread wide open as soon as the load 14 is jettisoned does not materially slow down the descent of said load; it, however, exerts a pulling force upon the loop formed by the braid. At a predetermined moment, this loop is broken by the load of explosive lighted up by the slow match 4, and the extracting parachute then exerts a pulling force upon the string 12 which pulls out and spreads open the main parachute out of its envelope 13.

As a modification and in order to cause the closed loop more safely to release the two bodies it connects together, it is sufficient to provide only one of the two rings 9, 10 secured to one of the bodies, the braid being secured to the other body in any suitable manner.

A similar braid 1 may be used for heavier loads provided the braid is formed into a double or multiple loop, each loop being engaged through both rings 9 and 10. The breaking of such a multiple loop at any point thereof ensures the separation of the two bodies connected together by said loop.

Operation of the igniting device 5 may be ensured by hand at the moment when the load is jettisoned or, preferably, by a pulling action exerted on the igniting device at the moment the load is jettisoned by a cable attached to the airplane.

While the invention has been described with particular reference to a preferred embodiment, it is not intended to limit the scope of the invention to the embodiment illustrated, nor otherwise than by the terms of the subjoined claims.

What is claimed is:

A destructible link device for releasably interconnecting two bodies, comprising, in combination, a tubular braid adapted to interconnect said bodies and having a

lateral opening, an explosive cartridge in said tubular braid, an ignition device for said cartridge located externally of said braid, and a slow match interconnecting said ignition device and said cartridge through said opening, said cartridge comprising a tubular envelope member of thermoplastic material having one end portion tightly connected to the inner end of said slow match and having its other end closed.
